BUFFING MECHANISM FOR CAR-PLATFORMS.

1,054,953.

Specification of Letters Patent.

Patented Mar. 4, 1913.

Application filed November 4, 1911. Serial No. 658,592.

To all whom it may concern:

Be it known that we, CHARLES T. WESTLAKE and CHARLES F. FREDE, citizens of the United States, residing at St. Louis, Missouri, have invented a certain new and useful Improvement in Buffing Mechanism for Car-Platforms, of which the following is a full, clear, and exact description, such as will enable others skilled in the art to which it appertains to make and use the same, reference being had to the accompanying drawings, forming part of this specification, in which—

Figure 1 is a top plan view of a cast metal platform with portions of the buffer beam and end sill and showing the buffing mechanism in position thereon. Fig. 2 is a longitudinal section taken approximately on the line 2—2 of Fig. 1. Fig. 3 is an enlarged section taken on the line 3—3 of Fig. 1. Fig. 4 is a transverse section taken on the line 4—4 of Fig. 1.

This invention relates generally to improvements in railway car platform construction and more particularly to the buffing mechanism applied to cast metal platforms, such as are now in general use in passenger car construction, and the principal objects of the invention are: to construct a skeleton platform and buffer beam so that a form of buffing mechanism of accepted M. C. B. type and now in use on a number of passenger cars may be readily applied to said platform and buffer beam and, further, to provide a construction wherein the operating parts of the buffing mechanism can readily be placed in or removed from position without detaching the vestibule or buffer from its stems, thereby permitting the buffing mechanism to be easily and quickly repaired when any of the operating parts have become broken or unfit for service.

With the above objects in view, our invention consists in certain novel features of construction and arrangements of parts hereinafter more fully described and claimed.

Referring in detail to the accompanying drawings: 1 designates the end sill of a cast metal car under frame of the type now in general use and formed integral with and projecting forwardly therefrom is a series of vertically disposed webs 2 and horizon-

tally disposed plates 3, which form a skeleton platform. Formed integral with the forward end of this skeleton platform is a buffer beam 4 of the usual box shape and positioned on top of the central portion of said beam is a threshold plate 5.

The numeral 6 designates a buffing member of the usual form which occupies a position immediately in front of the buffer beam, and positioned on top this buffing member is a plate 7 which is adapted to slide beneath the plate 5. The buffer 6 is carried upon the forward ends of a pair of side buffer stems 7 and the central portion of said buffer bears against the forward end of a center buffing stem 8. All of the buffer stems are arranged to slide freely through corresponding openings 9 formed in the front and rear walls of the buffer beam 4.

The numeral 2^a designates the pair of webs which occupy positions on opposite sides of the transverse center of the skeleton platform, and formed integral with the upper edges of these webs is a horizontally disposed plate 3^a. Formed integral with the webs 2^a and with the plate 3^a is a transversely disposed wall 10, through which is formed an opening 11, which is in alignment with the center buffer stem openings in the buffer beam.

The forward portion of the center buffer stem 8 is preferably square or non-circular in cross-section and the rear portion of the said stem is preferably round in cross-section, and positioned against the shoulder between the rounded rear portion and the square forward portion, is a disk or follower plate 12. A rear follower plate 13 is positioned on the rounded rear portion of the center stem and normally bears against the transverse wall 10, and mounted on the rounded rear portion of the center stem and interposed between the plates 12 and 13 is a comparatively heavy coil spring 14. The rear end of the center buffer stem 8 operates through the opening 11 in the transverse wall 10, and a pin or key 15, is inserted through the rear end of said center stem to the rear of said plate 10.

The numeral 16 designates transverse walls which are formed integral with the underside of the skeleton platform to the sides of the webs 2^a and formed through these walls 16, are openings 17, which are

in alinement with the side buffer stem openings through the buffer beam 4. Arranged for sliding movement in each of these openings 17, is a short tubular sleeve 18, which 5 serves as a bearing for the rear end of the corresponding side buffer stem. The rear ends of the said buffer stems extend through the collars 18 and mounted on said rear ends, are nuts 19. The forward portions 10 of the side buffer stems 7 are preferably square or non-circular in cross-section and the rear portions are round in cross-section.

Adapted to bear against the shoulders formed between the square or non-circular 15 forward portions and the round rear portions of these side stems, are disks or follower plates 20, and bearing against said plates are the forward ends of side buffer stem springs 21, the rear ends of which 20 bear against the forward ends of the collars 18.

Under normal conditions, the buffer springs 21 and 14 maintain the buffer 6 at its outward limit of movement, and when 25 said buffer is moved inward toward the beam 4, during the coupling of two cars, said springs will be compressed and will be therefore simultaneously thrown into action to yieldingly resist the inward movement of 30 the buffer and buffing mechanism, until said parts have been moved to such a degree as to permit the coupling of the cars.

The buffer stems are mounted to move 35 freely through their bearings and the springs mounted on said buffer stems readily combine to yieldingly resist any inward movement of the buffer.

The construction herein described is comparatively simple, provides a strong and

rigid support for the buffing gear, and the 40 entire buffing mechanism can be easily and quickly placed in operative position upon the platform and buffer beam or removed therefrom, without detaching the vestibule or the buffer from its stems, and, therefore, 45 said construction is especially advantageous when it is necessary to make repairs or to renew any parts which have become worn or broken in service.

It will be readily understood that minor 50 changes in the size, form and construction of the various parts of our improved buffing mechanism, can be made and substituted for those herein shown and described without departing from the spirit of our invention, 55 the scope of which is set forth in the appended claim.

We claim:—

In a buffing mechanism of the class described, the combination with a car end 60 sill and buffer beam, of a skeleton platform integral with said end sill and buffer beam, which platform comprises a series of longitudinally disposed members which are T-shape in cross section, a series of transversely disposed webs arranged between 65 said longitudinally disposed members, and bearings formed in said transversely disposed webs for the rear portions of the center and side buffer stems.

In testimony whereof we hereunto affix our signatures in the presence of two witnesses, this 28th day of October, 1911.

CHARLES T. WESTLAKE.

CHARLES F. FREDE.
